UNITED STATES PATENT OFFICE.

BERNHARD CLUSS, OF NEWARK, NEW JERSEY.

SPINNING TOP.

Application filed June 5, 1922. Serial No. 566,156.

To all whom it may concern:

Be it known that I, BERNHARD CLUSS, a citizen of the United States, residing at Newark, in the county of Essex and State 6 of New Jersey, have invented certain new and useful Improvements in Spinning Tops, of which the following is a specification.

This invention relates to spinning tops and particularly to such as are caused to 10 rotate by a whipping effect transmitted by a flexible strap connected with a rigid handle and some of its objects are, to provide a novel form of top, the outer surface of which may be either plain or helically 15 grooved to receive the lash element of the whip and the top may be provided with a metallic point if preferred.

A second object is to provide a whip in which the lash consists of a thin, narrow 20 leather strap to provide efficient adhesion to the surface of the top and also for its lasting qualities.

These objects are attained by the novel 25 design and construction of parts hereinafter described and shown in the annexed drawing, forming a material part of this disclosure, and in which:—

Figure 1 is a side elevational view showing a preferred embodiment of the top body.

30 Figure 2 is a bottom plan view of the same.

Figure 3 is a side view of a top body in its simplest form.

35 Figure 4 is a perspective view of the whip in its preferred form.

As will be seen from the drawings, the top body 10 in either form, is essentially conical, its side wall 11 being formed by parabolic curves with a rounded point or apex 12 40 at its smaller, lower end, while its upper end 13 is arcuately domed to a radius struck from a point corresponding with its tip.

Tops of this class are usually made of 45 considerable size and weight, preferably from hard wood and in order to avoid excessive wear are provided with a metal point 15, such as the rounded head of a tack or screw, the body 16 of which is embedded axially in the body of the top 50 while the curvature of the head 15 blends with the side of the top body and the body may be colored, polished and finished in any desired manner.

In the preferred embodiment, shown in 55 Fig. 1, a helical groove 17 is formed in the body beginning at a point slightly above the

juncture of the tip and sides and extending several times around the body to a point slightly above its center as shown, the helix being preferably counter clockwise or left 60 handed.

This groove is coarsely cut and the lash or strap 18 may initially be wound upon it, one edge of the strap being guided by the groove as it is wound from the point 19 at 65 the tip, after which the handle 20 is given a sharp whipping motion tending to cause the top to rotate at a high speed, maintained for a considerable period of time, due to the momentum imparted to it by the lash. 70

The velocity of the top may be maintained or increased as usual by blows of the whip, imparted at proper periods keeping it spinning and accelerating the speed as may 75 be desired.

While certain preferred embodiments of 80 this device have been shown and described, it will be understood that changes in the form, arrangements, proportions, sizes and details thereof may be made without departing from the scope of the invention as defined in the appended claims.

Having thus described my invention, what I claim as new and desire to secure by 85 Letters Patent, is:—

1. As a new article of manufacture, a block of hard wood formed to present a generical conical shape having parabolic side walls, an arcuate top joined by curves to said side walls, a flanged metallic head blending into the parabolic walls, on the lower end of said block, means for securing said head in axial position, and a coarse helical channel formed in the side walls from a point near the bottom to a point midway 90 in the height of the block.

2. As a new article of manufacture, a block of hard wood shaped to represent a top having parabolic side walls, a broad metal tip inserted in the apex of said block, 100 three or more relatively coarse convolutions of a left hand helical channel formed in said parabolic walls, a handle, and a leather lash fixed on one end in said handle, adapted to engage in the convolutions formed in the 105 sides of said block.

This specification signed and witnessed this 3rd day of June, 1922.

BERNHARD CLUSS.
